Primary Examiner — Marianne Pandozzi*(74) Attorney, Agent, or Firm* — Wenderoth, Lind & Ponack, L.P.(57) **CLAIM**

The ornamental design for a coffee dripper, as shown and described.

DESCRIPTION

FIG. 1 is a front elevation view of a coffee dripper showing my new design,

FIG. 2 is a top plan view thereof;

FIG. 3 is a left side elevation view thereof. A right side view thereof is the same as FIG. 3.

FIG. 4 is a bottom plan view thereof;

FIG. 5 is a sectional view according to the line 5-5 showing in FIG. 2.

FIG. 6 is a front elevational view thereof in folded position;

FIG. 7 is a top plan view thereof in folded position;

FIG. 8 is a bottom plan view thereof in folded position;

FIG. 9 is a bottom plan view thereof in folded position;

FIG. 10 is a sectional view according to the line 10-10 showing in FIG. 7.

FIG. 11 is an in use front elevational view of the coffee dripper; and,

FIG. 12 is an isometric view showing coffee dripper. The broken lines in the drawing depict environmental subject matter only and form no part of the claimed design.
